CLAIM

The ornamental design for dispenser of hygienic products for cleaning toilet, as shown and described.

DESCRIPTION

1. Dispenser of hygienic products for cleaning toilet
FIG. 1.1 is a bottom view of a dispenser of hygienic products for cleaning a toilet;

FIG. 1.2 is a top view thereof;

FIG. 1.3 is a first side view thereof;

FIG. 1.4 is a second side view thereof;

FIG. 1.5 is a third side view thereof;

FIG. 1.6 is a fourth side view thereof; and

FIG. 1.7 is a bottom perspective view thereof.

The broken lines shown in the drawings represent unclaimed portions of the dispenser of hygienic products for cleaning toilet and form no part of the claimed design.
